[57] **CLAIM**

The ornamental design for a toy glider, as shown and described.

DESCRIPTION

FIG. 1 is a top plan view of a toy glider showing my new design;

FIG. 2 is a side elevational view thereof, the other side being substantially a mirror image;

FIG. 3 is a front elevational view thereof;

FIG. 4 is a bottom plan view thereof; and,

FIG. 5 is a rear elevational view thereof.

FIG. 1

FIG. 2

FIG. 3

FIG. 4

FIG. 5
